UNITED STATES PATENT OFFICE.

WILHELM SCHMIDT AND PETER THOMSEN, OF WILHELMSHÖHE, NEAR CASSEL, GERMANY, ASSIGNORS TO SCHMIDT STEAM POWER PARENT CO., LTD., OF LONDON, ENGLAND, A FIRM.

SUPERHEATING DEVICE IN TUBULAR STEAM-BOILERS.

SPECIFICATION forming part of Letters Patent No. 703,482, dated July 1, 1902.

Application filed January 26, 1901. Serial No. 44,914. (No model.)

To all whom it may concern:

Be it known that we, WILHELM SCHMIDT and PETER THOMSEN, subjects of the King of Prussia, German Emperor, residents of Wilhelmshöhe, near Cassel, in the Province of Hesse-Nassau, German Empire, have jointly invented certain new and useful Improvements in Superheating Devices in Tubular Steam-Boilers, of which the following is an exact specification.

These improvements relate to superheaters which are arranged in large tubes in tubular boilers and offer the following advantages as compared with previous arrangements, viz: First, greater facility is given for cleaning and that from the smoke-box end; second, facility for replacing single pipes without removing the whole superheater; third, the application in a convenient manner of means for regulation even when several large superheaters and large boiler-tubes are used.

According to this invention the superheater-pipes in U form or serpentine form are made with an angular bend at the rear outlet of the boiler-tubes of the locomotive or other boiler, so that the superheater-pipes can terminate in suitable steam-inlet and steam-outlet chambers in the smoke-box. The boiler-tube can thus be cleaned without difficulty by a cleaning-tool or by a steam-jet or in any desired manner. The regulating device can therefore by reason of the aforesaid bending of the superheater-pipes and by reason of the boiler-tubes being open toward the smoke-box easily be applied and without impairing the access to the boiler-tubes.

In order to make our invention more clear, we refer to the accompanying drawings, in which similar letters denote similar parts throughout the different views, and in which—

Figure 1 is vertical longitudinal and Fig. 2 a vertical cross section of a superheater applied to a locomotive-boiler. Fig. 3 is an enlarged vertical longitudinal section of the superheater. Fig. 4 is a cross-section. Fig. 5 is a vertical longitudinal and Fig. 6 a vertical cross section of another arrangement where the superheater-pipes are bent backward and forward.

Referring to Figs. 1, 2, and 3, the steam from the steam-dome on the boiler enters the

steam-chamber *a* and passes by the lower openings *b* into the ends *c' c'* of the pipes *c*, which are bent and reach into the boiler-tubes *s* and have bends and return-pipes *c²*, 55 the ends *c³* of which are bent upward. The pipe ends *c'* and *c³* are made tight in the plate *p* by a tube-expander tool, and this plate is fixed to the steam-chamber *a* and a second steam-chamber *z*, which leads to the cylinder, 60 by means of bolts and nuts *d*.

r is a regulating-damper which when in horizontal position admits of perfect cleaning of the boiler-tubes.

As shown in Fig. 4, there may be a greater 65 number of boiler-tubes provided with superheater-pipes where a large superheating-surface is required.

In Figs. 5 and 6 the superheating-pipes run backward and forward in serpentine fashion 70 in a large boiler-tube *s*.

The superheating-pipes may be bent upward, downward, or sidewise, or in different directions, so long as the enlarged boiler-tube is clear of the steam-chambers *a* and *z*, and 75 thus permits of access.

It is to be noted as advantageous that the fixing of the bent pipe ends *c'* and *c³* does not take place directly in the steam-collectors *a z*, but in a plate *p*, whereby it becomes possible 80 to remove the whole of the superheater from the boiler-tube *s* without removing the steam-collectors *a z*.

Having thus fully described the nature of our invention, what we desire to secure by 85 Letters Patent of the United States is—

1. In locomotive and other steam-boilers, the combination with a steam-collector of a superheater consisting of superheating-pipes arranged in the boiler-tubes and having their 90 ends bent to the steam-collector, substantially as described and for the purpose set forth.

2. In locomotive and other steam-boilers, the combination with a steam-collector of a 95 superheater consisting of superheating-pipes arranged in the boiler-tubes and having their ends bent to the steam-collector, a regulating-damper behind the bends of the superheating-pipes, substantially as and for the 100 purpose set forth.

3. In locomotive and other steam-boilers,

the combination with a steam-collector of a superheater consisting of superheating-pipes arranged in the boiler-tubes and having their ends bent to the steam-collector, plates which are detachably fixed to the chambers and in which the superheating-pipe bends are fixed, a regulating-damper behind the bends of the superheating-pipe, substantially as described and for the purpose set forth.

10 In testimony whereof we have signed our

names to this specification in the presence of two subscribing witnesses.
